UNITED STATES PATENT OFFICE.

ELMER G. LANTZ AND MILO F. LANTZ, OF MARION, INDIANA.

COVER FOR PITCHERS.

SPECIFICATION forming part of Letters Patent No. 664,874, dated January 1, 1901.

Application filed September 18, 1899. Serial No. 730,885. (No model.)

To all whom it may concern:

Be it known that we, ELMER G. LANTZ and MILO F. LANTZ, citizens of the United States, residing at Marion, in the county of Grant and State of Indiana, have invented a new and useful Improvement in Covers for Pitchers, of which the following is a specification.

This invention is a new and useful construction of pitcher-cover, one object being to provide an exceedingly cheap and simple device which will effectively close the mouth of the pitcher when in an upright position and will automatically open the lid when the pitcher is tilted to discharge its contents.

Another object of the invention is to provide a device of such construction that the operative mechanism will not come in contact with the contents of the vessel, but will act at all times.

With these various objects in view the invention consists in certain details of construction and novelties of combination, all of which will be fully described hereinafter and pointed out in the claims.

In the drawings forming part of this specification, Figure 1 is an elevation showing the top portion of the pitcher provided with our invention, the operating mechanism being shown through the glass. Fig. 2 is a similar view showing the position the parts assume when pouring the contents from the pitcher. Fig. 3 is an inverted plan view of the cover and depending weight.

Referring more particularly to the drawings, A indicates a pitcher of any desired construction, the upper portion only of which is shown in the drawings. The rear portion of the top of the pitcher is preferably extended slightly upward, as shown at A², and provided with suitable bearings at the forward ends of the extended portions. The lid or cover C is pivotally secured at the top of the pitcher, the rear portion being preferably cut away to fit within the extension or collar at the rear. The pivot for the lid is preferably formed from a wire rod, which has its ends projecting through ears D⁶ to form pivots or journals D⁵, which are adapted to fit in the bearings in the sides of the pitcher and permit of the swinging of the lid or cover. The central portion D' of the rod is provided with a weight E, preferably in the form of a

ball. The portions of the rod between the central portion D' and the pivotal ends are bent first to the rear, as shown at D², then 55 bent forwardly, as shown at D³, to a point beyond the pivots, and then curved slightly to the rear and outward, forming a shoulder D⁴, which engages with the ears D⁶. The portion D² is bent at such an angle to the portions D³ that the weight or ball E will be located at such a distance below the pivots as to hold the cover in a substantially horizontal position. When constructed in this manner, it is evident that the cover may be easily 65 secured to the top of the pitcher by compressing the bent portions laterally to a sufficient extent to withdraw the pivots through the ears until the ears can be passed down within the collar at the top of the pitcher, 70 when the pressure upon the rod can be released and the pivots will be instantly forced laterally into their bearings. When the pitcher stands in its upright position, the weight upon the rod will hold the cover in a 75 horizontal position, causing it to close the top of the pitcher. As soon, however, as the pitcher is turned forward to pour its contents out at the spout the cover will retain its horizontal position, which will cause its forward end to be separated from the spout of the pitcher a sufficient distance to permit the passage of the contents without engaging with the cover. Upon returning the pitcher to its normal position the spout will be again brought 85 into contact with the forward end of the cover, and the pitcher will be closed, as before.

Although we have shown and described the pitcher as formed from glass, it is evident that it can be formed from any other material, and 90 we reserve the right to make such a change and also all other changes and variations which will come within the limit and scope of our invention.

Having thus fully described our invention, 95 what we claim as new, and desire to obtain by Letters Patent of the United States, is—

1. In a device of the kind described, the combination with the pitcher or other receptacle having bearings in the sides thereof, of 100 a lid or cover provided with bearings, laterally-movable pivots or journals in the bearings of the cover adapted to enter the bearings of the pitcher, said journals being pro-

vided with bent portions to engage with the cover to the front and rear of the bearings and having the central portion bent forwardly and downwardly, and a weight on the downwardly-bent portion.

2. A cover for pitchers and similar vessels, having a weighted bar secured to the under face thereof, said bar having upwardly and backwardly projecting extensions bent for-

wardly to lie against the surface of the cover and terminating in journals adapted to enter openings in the pitcher, substantially as described.
